APPARATUS FOR MANUFACTURING
CLOTHESPINS

Bert B. Sweet, Akron, Ohio

Application August 30, 1949, Serial No. 113,122

1 Claim. (Cl. 29—34)

1

This invention relates to apparatus for producing metal clothes pins.

The clothes pin is preferably formed by doubling a narrow, flat strip of metal at its middle. The legs of the clothes pin are straight except that they are flared slightly at their outer ends. Preferably the legs are not parallel but diverge slightly from the arched portion which connects the two legs, making the pin somewhat wedge-shaped. The farther a clothes line is forced between the legs of the pin the tighter the pin will grip the line. Preferably the inside surface of each leg is embossed or otherwise roughened to give added holding power.

This pin has many advantages over the conventional wooden or plastic pins now on the market. It is small, for example, about one and one-half inch long, and light, so that a number of them may be held in one hand. Being metal, it is easily cleaned and inexpensively manufactured.

The clothes pins may be manufactured advantageously on a mass production basis with the preferred apparatus of this invention. This preferred apparatus includes a novel, single-action die and corresponding punches therefor. They are adaptable to conventional punch presses. The stock from which the pins are made is fed into the press from a roll in the form of a continuous ribbon. On a single stroke of the press, a sufficient length of the stock for the formation of a clothes pin is sheared from this ribbon and then doubled to form the pin. Embossing rollers form depressions on the outer surface of each leg and bosses on the inner surface, as the material is doubled. The finished pin is ejected as the punches move upward and then more of the stock is fed into proper position on the die ready for a repetition of the above operation. No handling of the pin is necessary. It is completely formed in one operation.

The invention will be further described with reference to the accompanying drawings, in which—

Fig. 1 is a side elevation of the clothes pin;

Fig. 2 is a view taken from the right side of Fig. 1;

Fig. 3 is an enlarged cross-sectional view of a leg of the pin taken on the line 3—3 of Fig. 1;

2

Fig. 4 is an enlarged cross-sectional view taken on the line 4—4 of Fig. 1;

Fig. 5 is a plan view of a preferred die used in the manufacture of the pins;

Fig. 6 is a cross-sectional front elevation of the die and punches therefor taken on the line 6—6 of Fig. 7, except that the die and punches as shown in Fig. 6 are in closed position;

Fig. 7 is a cross-sectional side elevation of the die and shaping punch showing them in open position;

Fig. 8 is an enlarged plan view of the die rollers which shape the outside of the pin;

Fig. 9 is an enlarged plan view of the embossing rollers of the die;

Fig. 10 is an enlarged cross-sectional view of the shaping punch taken on the line 10—10 of Fig. 7;

Fig. 11 is an enlarged cross-sectional view of the cut-off punch taken along line 11—11 of Fig. 12; and

Fig. 12 is an enlarged side elevation of the lower end of the cut-off punch.

The clothes pin 1 is formed of a narrow, flat strip of resilient metal, preferably steel or aluminum. The legs 3 of the pin are connected together at one end by the arched portion 4. The legs are substantially straight and flat throughout their length except that the outer end of each is flared slightly at 5 so that they may be easily slipped over a clothes line. These ends are advantageously only slightly flared. If more than slightly flared, when a number of pins are packed into a box, the flared end of a leg of one pin easily becomes tightly jammed between the legs of other pins in the box, so that they are difficult to separate.

Preferably the legs are not parallel but diverge slightly from the arch 4. The outer end of each leg is also radiused at 7 and the outside corners 8 along the longitudinal edges 9 of each leg are rounded.

A plurality of parallel, lateral grooves 11 are pressed into the outside surface of each leg of a pin as it is shaped. The inside surface of each leg is embossed with parallel bosses 13, each being opposite one of the grooves 11 as shown in Figs. 3 and 4. The grooves 11 roughen the outer surface of the legs and make them easily grasped when they are being slipped onto a clothes line.

or removed therefrom. The embossed inner surface gives the pins a stronger grip when fastening clothes to a clothes line.

The die used in the manufacture of these pins is provided with a stock cut-off matrix 20, a shaping matrix 21, and a stop 22 which measures the length of stock needed to form one pin. These matrices are fastened to a suitable die shoe 24 which in turn is mounted to the bed or bolster 25 of a punch press 27. The punches 30 and 31 used in conjunction with the matrices 20 and 21 respectively are bolted to punch shoe 33 which in turn is fastened to the reciprocating head 34 of the punch press. Cut-off punch 30 moves into and out of matrix 20 and shaping punch 31 moves into and out of matrix 21 as the head of the press reciprocates. Vertical guide pins 36 are provided at the rear corners of the die shoe. These slide into appropriate openings in the punch shoe and keep each punch properly aligned with its respective matrix during the impact strokes of the press.

In forming the pins, the stock, a metal ribbon 38, is fed from a roll 39. This stock is brought across the top of matrices 20 and 21 and the end of the stock fits into the recessed portion 41 of the stop.

As the head of the press moves down at the start of an operating stroke, cut-off punch 30, being slightly longer than shaping punch 31, strikes the ribbon of stock first. The cutting edge 43 (Fig. 12) of this punch is notched slightly at 45 where it contacts the stock so that the stock is centered properly on each stroke of the press. Opposite sides of punch 30 are provided with concavities 46, the radius of each being equal to the radius 7 at the end of each leg. The cut-off matrix 20 is formed of two upright plates 47 disposed laterally of the die shoe. The inner face of each plate is provided with a convex boss 49, also substantially equal to radius 7. Cut-off punch 30 moves up and down between the plates 47 with the concavities 46 in mating relation with the convex bosses 49; there being sufficient clearance between them so that the punch does not contact any portion of the matrix.

Cut-off punch 30 strikes the stock 38 and shears through the portion between the sharp edges around the top of each boss 49. This punch forms a radius 7 on the end of the length of stock cut off to be doubled to form a pin, and also on the end of the stock strip which will be moved across the matrices and into recess 41 of the stop at the start of the next succeeding stroke of the press. A recess 51 (Fig. 6) is provided in the die shoe between plates 47 to collect the cutout scraps.

Immediately after the cut-off punch 30 shears off the measured length of the ribbon, the end of the shaping punch 31 strikes it and doubles it by forcing its mid-section into the matrix 21. This matrix is provided with two parallel rollers 54 between which the punch 31 moves up and down, and these are supported between the parallel plates 56. The center portion 57 of each roller is of smaller diameter than the remainder of the roll and the shoulder at each side of this center section is radiused at 59. These rollers double the length of stock when punch 31 forces it between them. The radiused portions 59 compress the edges of the stock to form the radius 8 along each outside edge of the finished pin.

A second pair of parallel rollers 61 (Fig. 9) is located just below rollers 54. The center portion of these rollers is provided with parallel, peripheral teeth 62. After punch 31 has forced the

stock between rollers 54 it forces it between rollers 61, and teeth 62 bite into the metal surface and form the grooves 11 on what will be the outside surface of the finished pin. The lower central portion of opposite lateral surfaces of punch 31 is undercut a few thousandths of an inch at 64 (Figs. 7 and 10) so that as the teeth form the grooves, the metal opposite each groove is bulged out slightly into this undercut area 64, forming a boss 13 on the inside surface of each leg of the pin opposite each groove 11.

Fig. 6 shows the die and punches in closed position after a pin is completely shaped. The lower edge of punch 31 is rounded somewhat to form the arch 4 of the pin. The upper portion of each side of the punch is curved outwardly at 68 to form the flared ends 5 of the finished pin.

An ejector 69 is provided in die shoe 24 and is enclosed in a tube which projects below the die shoe through the hole 70 in the center of the bolster. This ejector extends upwardly between the rollers. As punch 31 forces the length of stock down between the rollers it compresses spring 71 located under the base of the ejector. When the punch is withdrawn from the matrix this spring expands and lifts the ejector which holds the newly formed pin in contact with the punch until the pin is clear of the matrix. The conventional presses used for dies of the type described may be adjusted to operate with the bolster plate at an angle to the horizontal as shown in Fig. 7. Operating at such an angle, as soon as the newly formed pin 1 is clear of the ejector, it will drop off punch 31 into a suitable hopper or tray 73.

To summarize the method of forming the clothes pin, the stock for forming a pin is first measured from a roll and then this length is sheared off by a die punch which enters a cut-off matrix of the die just as the head of the press starts downward. This punch rounds the ends of the length of stock. Immediately thereafter a second punch doubles this piece by forcing the middle portion of the stock into a shaping matrix. The pin is properly shaped, the outer edges are rounded, grooves are formed on the outer surface of the legs and the inner surface is embossed, all in one operation. On the return stroke of the press, the ejector removes the finished pin and the equipment is clear and ready for a repetition of the operation as described.

Modifications may be made in the equipment without departing from the scope of the appended claim. For instance, it is not essential that the outer corners of the pin be rounded. It is not necessary that the bosses 13 be formed on the inner surface of the pin, although this makes the pin more efficient. In the equipment, any suitable automatic feed, properly timed with the action of the press, may be used for supplying stock to the die. Although particularly designed to fasten clothes on a clothes line, the pin may be used for fastening draperies and the like, and for other uses.

What I claim is:

Apparatus for manufacturing a clothes pin from a flat metal strip, which includes a pair of spaced, parallel rollers, and adjacent thereto a second pair of spaced parallel rollers, the opening between the first pair of said rollers being in register with the opening between the second pair of said rollers, the central portion of each roller of the first pair being of smaller diameter than the end portions and the shoulders at each end of the

central portion being radiused to round the corners of the pin, and each of the rollers of the second pair having radially projecting teeth on the periphery, and a punch for reciprocating into and out of the space between the pairs of rollers, the walls of the punch outwardly adjacent the portion between the first pair of rollers at the end of the inward movement of the punch being flared slightly outwardly, the central portion of the punch opposite the teeth being undercut.
